UNITED STATES PATENT OFFICE.

PETER SJOSTROM, OF MAPLEWOOD, MASSACHUSETTS, ASSIGNOR TO VICTOR SHOE MACHINERY COMPANY, OF LYNN, MASSACHUSETTS, A CORPORATION OF MASSACHUSETTS.

EDGE-GAGE FOR SEWING-MACHINES.

1,177,285.

Specification of Letters Patent. Patented Mar. 28, 1916.

Application filed April 24, 1915. Serial No. 24,133.

To all whom it may concern:

Be it known that I, PETER SJOSTROM, a subject of the King of Sweden, and a resident of Maplewood, in the county of Middlesex and State of Massachusetts, have invented certain new and useful Improvements in Edge-Gages for Sewing-Machines, of which the following is a specification.

This invention relates to edge gages, for 10 sewing machines especially adapted for sewing boots and shoes, and has for its object the production of a device of this character which will be simple and inexpensive to make while very effective in its operation.

15 The present invention is particularly adapted to be applied to a machine such as is fully shown and described in another application of mine filed February 17, 1915, and numbered 9,465, and to which reference 20 may be made for the complete operation of the machine.

The invention consists in certain novel features of construction and arrangement of parts which will be fully understood by reference to the description of the drawings 25 and to the claims hereinafter given.

Of the drawings: Figure 1 represents a side elevation of a device embodying the principles of the present invention, and Fig. 2 30 represents a front elevation of the same.

Similar characters designate like parts throughout the several figures of the drawings.

In the drawings, 10 is a portion of the 35 frame of a sewing machine provided with a pivot member 11 extending laterally therefrom on which is mounted a lever 12 having an upwardly curved arm the extreme upper end 13 of which is parallel with the front of 40 the machine and rests upon the work support 14 of any well-known construction.

The work 15 is retained in contact with the work support 14 by means of the usual presser foot 17 and the edge of said work 15 45 bears against the front face of the portion 13 of the lever 12 and is fed in the usual manner while contacting therewith. The lever 12 is provided with a downwardly extending arm 18 having an ear 19 projecting laterally therefrom in front of the frame 10. This ear 19 is provided with an opening 20 therethrough, somewhat larger than the shank 21 of an adjusting screw, the head 22 of which bears against the outer face of 55 the ear 19. The shank 21 is threaded to the

frame 10 and may be adjusted relatively thereto to regulate the position of the bearing portion 13 of the lever 12 relatively to the work support 14.

Surrounding the shank 21 and interposed 60 between the front face of the frame 10 and the rear face of the ear 19 is an expansion spring 23 the pressure of which retains the front face of the ear 19 in frictional contact with the head 22 of the adjusting screw and 65 thereby prevents its accidental rotation.

The lever 12 may be made of sheet metal stamped into shape and thereby reduce the expense of manufacture.

As the head 22 is moved outwardly from 70 the frame 10 the spring 23 will cause the ear 19 to follow outwardly, thereby increasing the distance between the front face of the gage 13 and the front edge of the work support 14.

75 This makes a very simple but effective edge gage for sewing machines which may be readily applied at slight expense to almost any style of boot and shoe sewing machine.

It is believed that the operation and many 80 advantages of this invention will be fully apparent from the foregoing description.

Having thus described my invention, I claim:

1. The combination with a work support 85 and a frame in which said support is mounted, a lever pivoted to said frame in a plane below said work support having a curved extension adapted to form an edge gage and provided with a radial arm below its pivot; 90 and means coacting with said arm for adjusting said lever about its pivot lever consisting of a member movably mounted on said frame.

2. The combination with a work support 95 and a frame in which said support is mounted, a lever pivoted to said frame in a plane below said work support having a curved extension adapted to form an edge gage and provided with a radial arm below its pivot; 100 and means coacting with said arm for adjusting said lever about its pivot consisting of a headed member extending through a slot in said arm and threaded to said frame.

3. The combination with a work support 105 and a frame in which said support is mounted, a lever pivoted to said frame in a plane below said work support having a curved extension adapted to form an edge gage and provided with a radial arm below its pivot; 110

means coacting with said arm for adjusting said lever about its pivot consisting of a headed member extending through a slot in said arm and threaded to said frame; and a 5 spring for retaining said arm in contact with the head of said adjusting member.

4. The combination with a work support and a frame in which said support is mounted, a lever pivoted to said frame in a plane 10 below said work support having a curved extension adapted to form an edge gage and provided with an oppositely disposed arm having a slotted ear; an adjusting member having a shank extending through the 15 slot in said ear and threaded to said frame and provided with a head forming a stop to limit the movement of said lever in one direction about its pivot.

5. The combination with a work support

and a frame in which said support is mounted, a lever pivoted to said frame in a plane below said work support having a curved extension adapted to form an edge gage and provided with an oppositely disposed arm having a slotted ear; an adjusting member 25 having a shank extending through the slot in said ear and threaded to said frame and provided with a head forming a stop to limit the movement of said lever in one direction about its pivot; and a spring for retaining 30 said ear in contact with said head.

Signed by me at 4 Post Office Sq., Boston, Mass., this 23rd day of April, 1915.

PETER SJOSTROM.
